UNITED STATES PATENT OFFICE.

BENJAMIN DENVER COPPAGE, OF WILMINGTON, DELAWARE.

COMBINED CONVEYER AND SCRAPER FOR CENTRIFUGAL MACHINES.

1,028,934.

Specification of Letters Patent. Patented June 11, 1912.

Application filed September 16, 1911. Serial No. 649,606.

To all whom it may concern:

Be it known that I, BENJAMIN DENVER COPPAGE, of Wilmington, Delaware, have invented a new and useful Improvement in Combined Conveyers and Scrapers for Centrifugal Machines, which invention is fully set forth in the following specification.

In using a centrifugal machine of the type illustrated in U. S. Letters Patent to 10 C. S. Lee, No. 882,256, dated March 17, 1908, a clearance between the peripheral edge of the fixed spiral conveyor blade or blades and the inner surface of the rotatable cylindrical screen or rotor results in the 15 formation about the inner surface of the perforated wall of the drum of a thin covering of the material being acted upon. In drying sand, for example, the thin covering of sand thus formed permits water to drain 20 therethrough and be discharged through the perforations of the rotor by the centrifugal action. But in acting upon other materials, such for example as coal, for drying the same preparatory to coking, which coal contains 25 small portions of clay, or coal dust, or both, there is a tendency to form about the interior surface of the rotor a tightly compacted covering which is impervious to water and hence interferes with the expulsion 30 of the water therethrough and through the perforations of the rotor by centrifugal action. As a covering of material about the interior surface of the rotor affords a frictional contact with and grip upon the 35 main body of the material in the rotor in causing said material to be whirled about with the rotor, such covering is in that respect an advantage.

My present invention provides a combined conveyor and scraper designed—particularly as to those materials which tend to form a compact and impervious covering—to scrape a sufficient area of the interior surface of the rotor to permit the 45 expulsion, through the perforated wall of the drum, of the water to be extracted, and also adapted to advance the material being acted upon through the drum at the desired speed of travel.

Reference to the accompanying drawing 50 illustrating one embodiment thereof will facilitate an understanding of the invention and a detailed description thereof. In said drawing, Figure 1 is a longitudinal section 55 through a rotatable perforated screen, cylinder or drum and the combined scraper

and conveyor within the same; and Fig. 2 is a transverse section through the same.

In dotted lines, there is shown a portion of a rotatable perforated or foraminated 60 screen, cylinder or drum 5, designated the "rotor".

6 is a fixed shaft or core extending axially through the rotor and preferably square in cross-section. From said shaft there is supported what is in effect a single flight spiral ribbon conveyor made up of repeated groups of successive approximately quarter-circle overlapping sections 7, 8, 9 and 10. The section 7 is adapted to contact the inner 70 surface of the rotor and act not only to advance material but also to scrape from a portion of the interior surface of the rotor which it contacts any coating or covering of material which forms thereon. Said section 7 is secured to the outer end of an arm 11, the inner forked end of which embraces and is pivoted to the core 6 by a bolt 12. Pressure yieldingly applied to the arm 11 through a bolt 13 acting upon a rubber or 80 spring buffer 14 seated against a shoulder on the arm, acts to hold the edge of the section 7 in contact with the surface of the rotor 5. The end of section 7 slightly overlaps the end of section 8, which in turn 85 slightly overlaps section 9. Section 9 overlaps section 10, which latter overlaps a second section 7; and so on. Section 9, for example, is secured to an inclined arm 15, the forked inner end of which embraces 90 and is pivoted to core 6 by a bolt 16. The material carried against the inclined face of section 9 by rotation of the rotor tends to swing said section outward into contact with the inner surface of rotor 5. To prevent this and preserve a desired clearance between the edge of section 9 and the surface of the drum, a bolt 17 carried by the arm 15 contacts core 6. Bolt 17 is adjustable to vary the clearance between the edge 95 9 and the rotor wall. Sections 8 and 10 are also carried by arms similar to arm 15 and having adjustable stops similar to bolt 17 for preserving the desired clearance between the edges of these sections and the wall of 100 the rotor.

In the operation of the machine, in which the rotor is operated at high speed—such as one thousand revolutions a minute—the section or sections 7 of the blade in contact 110 with the rotor scrape from a portion of the interior surface of the rotor any cover-

ing of the material tending to form thereon, while the other sections, by reason of their slight clearance from the rotor, permit a thin layer around parts of the inner 5 surface of the rotor, which layer affords a frictional contact with and grip upon the main body of the material, as before stated.

What I claim is—

1. In a centrifugal machine, the combination with a perforated drum or rotor, of a spiral conveyer blade in said rotor formed of a succession of overlapping sections each movable independently of other sections with relation to the interior surface of the 15 rotor.
2. In a centrifugal machine, the combination with a perforated drum or rotor, of a core extending longitudinally in said rotor, and a spiral conveyer blade in said rotor 20 formed in sections each pivotally supported from said core for movement toward or from the interior surface of the rotor.
3. In a centrifugal machine, the combina-

tion with a perforated drum or rotor, of a core extending longitudinally in said rotor, 25 a spiral conveyer blade in said rotor formed in sections, and supporting arms extending between said core and said blade sections respectively, each arm being secured at its outer end to its blade section and at its inner end 30 pivotally joined to the core.

4. In a centrifugal machine, the combination with a perforated drum or rotor, of a spiral conveyer blade in said rotor formed of a succession of sections, means supporting said sections in the rotor, and means 35 yieldingly holding some of said sections in contact with the inner surface of the rotor.

In testimony whereof I have signed this specification in the presence of two subscribing witnesses.

BENJAMIN DENVER COPPAGE.
